(57) **CLAIM**

The ornamental design for a low-profile art frame, as shown and described.

DESCRIPTION

FIG. 1 is a front perspective view of the first embodiment of the low-profile art frame;

FIG. 2 is a front elevation view of the first embodiment of the low-profile art frame;

FIG. 3 is a rear elevation view of the first embodiment of the low-profile art frame;

FIG. 4 is a right side elevation view of the first embodiment of the low-profile art frame;

FIG. 5 is a left side elevation view of the first embodiment of the low-profile art frame;

FIG. 6 is a top view of the first embodiment of the low-profile art frame;

FIG. 7 is a bottom view of an embodiment of the low-profile art frame;

FIG. 8 is a rear perspective view of the first embodiment of the low-profile art frame;

FIG. 9 is a front perspective view of the second embodiment of low-profile art frame;

FIG. 10 is a front elevation view of the second embodiment of the low-profile art frame;

FIG. 11 is a rear elevation view of the second embodiment of the low-profile art frame;

FIG. 12 is a right side view of the second embodiment of the low-profile art frame;

FIG. 13 is a left side view of the second embodiment of the low-profile art frame;

FIG. 14 is a top view of the second embodiment of the low-profile art frame;

FIG. 15 is a bottom view of the second embodiment of the low-profile art frame; and,

FIG. 16 is a rear perspective view of the second embodiment of the low-profile art frame.

The broken lines illustrate portions of the low-profile art frame that form no part of the claimed design.

1 Claim, 10 Drawing Sheets
